UNITED STATES PATENT OFFICE

LOUIS L. HOSKINSON, OF CLINTON, IOWA

WATER MOTOR

Application filed March 4, 1927. Serial No. 172,901.

This invention relates to a water motor, the general object of the invention being to provide a wheel with its blades or paddles movably arranged and having their movement limited so that they will resist the movement of the water entering the wheel, but will move with the water leaving the wheel so that the wheel can be operated by a current of water without necessitating the wheel being placed under a waterfall.

Another object of the invention is to provide means for directing the water against the wheel in such a manner as to secure its maximum propelling effect.

15 This invention also consists in certain other features of construction and in the combination and arrangement of the several parts, to be hereinafter fully described, illustrated in the accompanying drawings and specifically 20 pointed out in the appended claim.

In describing my invention in detail, reference will be had to the accompanying drawings wherein like characters denote like or 25 corresponding parts throughout the several views, and in which:—

Figure 1 is a plan view of the apparatus.
Figure 2 is a side view.

Figure 3 is a section on line 3—3 of Figure 1.

30 Figure 4 is a section on line 4—4 of Figure 2.

In these views, A indicates the flume forming casing which has a flat bottom 1, the flat sides 2 having their front ends diverging, as 35 at 3, and the top piece formed with a semi-circular central portion 4, and upwardly and outwardly inclined end pieces 5 and 5', the front end piece 5 having its edges diverging to fit the diverging parts 3 of the side pieces 40 and the rear end piece 5' being of less length than the rear part of the casing. The front part is provided with a false floor 1' which extends upwardly and inwardly at an angle and forms with the part 5 and the parts 45 3 a gradually decreasing mouth or inlet at the front end of the casing for directing the water entering the same against the wheel B in the central part of the casing. This wheel comprises the end pieces 6 which are fastened 50 to the horizontal shaft 7 which is journaled

in the side pieces of the casing and the blades 8 which are pivotally secured to the end pieces through means of the rods 9 which are arranged in an annular row adjacent the shaft 7. An outer row of rods 10 is carried by the end pieces 6, the row being arranged adjacent the periphery of the wheel and these rods act as stops for limiting the movement of the blades. As will be seen, the wheel extends into the space formed by the part 4 of the top of the casing and the central extension of the side pieces thereof.

I provide the wheel with an odd number of blades or paddles, the drawings showing the wheel provided with seven blades. Of course, it is to be understood that I do not wish to be limited to this number. By providing an odd number, the blades in the lower part of the wheel will lie closer together than the blades in the upper part of the wheel.

As will be seen from Figure 3, the water entering the mouth of the casing will be directed against the blades moving downwardly with the wheel so that the pressure exerted by the current of water will operate against the blades, forcing them against the bars 10 and thus rotating the wheel. When the blade moves to a position where it is acted on by the water leaving the wheel, it will assume a horizontal position so as to offer no resistance to the passage of this water and it will finally drop back upon the next rod 10 from the one which it had been previously engaging so that the blade will be carried upwardly until it reaches a vertical position at the top of the wheel, when it will drop forwardly, as soon as it starts on its downward movement, until it strikes the rod 10 in front of it.

From the foregoing it will be seen that with this wheel composed of the movable blades, the device can be placed in streams of water which have but little current and it is not necessary to build dams or the like to create a waterfall or a swift current to operate the device. Thus this apparatus can be used in level countries and the improved wheel will secure the maximum amount of power from a slow current.

Power can be taken from the wheel such

as by mounting a shaft 11 on the supports 12 and belting or otherwise connecting it with the shaft 7, this shaft 11 being adapted to be connected to a device to be driven.

5 It is thought from the foregoing description that the advantages and novel features of my invention will be readily apparent.

I desire it to be understood that I may make 10 changes in the construction and in the combination and arrangement of the several parts, provided that such changes fall within the scope of the appended claim.

What I claim is:—

15 A water motor comprising a casing having an inlet at its front end composed of convergent upper and lower walls and convergent side walls, said casing having a flat bottom, the forward part of which extends under the lower wall of the inlet, the rear and intermediate parts of the casing having straight 20 side walls, a substantially semi-circular top wall at the center of the casing, the front edge of which is connected with the inner edge of the top wall of the inlet, an upwardly and rearwardly extending top wall for the rear of the casing having its front edge connected with the lower edge of the semi-circular wall, said upwardly and rearwardly extending wall terminating short of the ends of the rear part 25 of the casing and a water wheel at the center of the casing, with portions extending into the space formed by the semi-circular wall.

30 In testimony whereof I affix my signature.
35 LOUIS L. HOSKINSON.
